Specification for Design.

Patented Mar. 21, 1922.

Application filed November 8, 1920. Serial No. 422,745. Term of patent 14 years.

To all whom it may concern:

Be it known that I, JOHN R. KERNS, a citizen of the United States, residing in Covington, in the county of Kenton and State of Kentucky, have invented a new, original, and ornamental Design for Lamps, of which the following is a specification, reference being had to the accompanying drawing, forming part thereof.

The figure is an isometric view of a lamp, showing my new design, the glass being green.

I claim:

The ornamental design for a lamp, as shown.

JOHN R. KEARNS.
